UNITED STATES PATENT OFFICE.

GOVERNIER W. MORTON, OF WASHINGTON, DISTRICT OF COLUMBIA, ASSIGNOR OF ONE-FOURTH TO CHANDLEE & CHANDLEE, OF WASHINGTON, DISTRICT OF COLUMBIA.

AERIAL TOY.

No. 862,094.

Specification of Letters Patent.

Patented July 30, 1907.

Application filed November 1, 1906. Serial No. 341,575.

To all whom it may concern:

Be it known that I, GOVERNIER WISE MORTON, a citizen of the United States, residing at Washington, in the District of Columbia, have invented certain new and useful Improvements in Aerial Toys; and I do hereby declare the following to be a full, clear, and exact description of the invention, such as will enable others skilled in the art to which it appertains to make and use the same.

10 This invention relates to toys and more particularly to aerial toys.

The primary object of the invention is to provide an extremely simple toy of novel construction and of the class mentioned which may be thrown upwardly and 15 forwardly into the air and which will return to the thrower and a further object of the invention is to provide a toy of this class which may be manufactured from a single piece of material either by stamping or otherwise and may hence be placed upon the market 20 at an extremely low cost.

Broadly stated the toy consists of a central web portion provided with a central aperture and blades which radiate from the web portion and are provided in their under faces with channels.

25 The principle involved in the device is that when thrown into the air substantially at an angle of forty-five degrees, and when it starts to descend, air will be compressed in the channels in the under face of the blades and will pass therethrough to the opening 30 formed centrally in the web portion of the toy, this compression of air beneath the blades serving to sustain the toy for a considerable length of time in the air. This compression of air is in fact so considerable that the toy will almost invariably descend to a plane 35 below that from which it was started on its flight and will thence rise to the plane.

In throwing the toy, it is grasped loosely by one of the blades and is tossed into the air with an upward inclination, the arm being drawn backwardly with a 40 snap so as to give to the toy a rotary movement. The result is that the toy after ascending an inclined plane the distance depending upon the force with which it is thrown, returns to a point slightly below that from which it was launched.

45 In the accompanying drawings—Figure 1 is a bottom plan view of the preferred form of the toy. Fig. 2 is a detail sectional view taken therethrough. Fig. 3 is a view similar to Fig. 1 showing a further modification of the toy. Fig. 4 is a similar view on the same 50 line as the form shown in Fig. 3 and, Fig. 5 is a view similar to Fig. 1 showing another modification.

Referring more specifically to the drawings and more particularly to Figs. 1 and 2 thereof the numeral 10 denotes the central or web portion of the toy which

may be of any desired configuration and size and 11 55 an opening which is formed centrally of the web portion. The purpose of the opening above described will be presently fully stated and it may be here said that the opening is of such size as will be found expedient.

60 Radiating from the web portion 10 of the toy are blades 12 and its blades are here shown as being four in number although a greater or less number may be employed if found to be desirable. Each of the blades 12 is provided in its under face with a channel 13 and 65 although I have herein shown the entire device formed of sheet material and the channels in the blades formed by creasing the same longitudinally, the blades and the web portion, which is also creased correspondingly as at 14, may be made of any suitable material having 70 its upper face of any contour desirable, the sole limitation being that the under face of the blade must be provided with a channel. The channels in the under face of the blades and also the channels formed by creasing the web portion 10 of the toy all communicate 75 with the opening 11 formed centrally in the web portion.

It will be readily understood that when the toy is thrown into the air at substantially an angle of forty-five degrees and starts to descend, air will be compressed 80 in the channels 13 of the blades and will pass therefrom through the opening 11 in the web portion, this compression of air serving effectually to sustain the toy for a considerable length of time in its aerial flight.

It will be observed that by creasing the blades and 85 also the web portion of the toy, in the manner stated, the web portion will be located in a slightly higher plane than the extreme ends of the blades and hence the flow of the air compressed beneath the blades to and through the opening 11 formed in the web portion, 90 will result.

In the form of my invention shown in Fig. 3 the web portion is indicated by the numeral 10^a and the central opening in the web portion by the numeral 11^a the blades being indicated by the numeral 12^a and the 95 channels in the blades by the numeral 13^a. In this form of the invention however the blades are braced by means of connecting portions 15 which connect adjacent ones of the blades and at the point of intersection of the connecting portions with the blades, openings 100 16 are formed. The channels in the under face of the blades however do not terminate at these openings but are continued to the central opening 11^a in the web portion.

In the form of my invention shown in Fig. 4, sub- 105 stantially the same lines are followed as in Fig. 3, the parts of the toy as shown in this figure corresponding to the parts shown in Fig. 3 being indicated by the same

numerals with the suffix *b*. In the form shown in Fig. 4 however the inter-space between the adjacent blades and the connecting portion 14 of the blades is closed by means of sheets 16' of tissue paper or other light material which aid considerably in sustaining the toy during its descent.

In the form of my invention shown in Fig. 5 the parts corresponding to the various parts in Fig. 1 are indicated by the same reference numerals with the addition of the suffix *c* and in this form of the invention the web is substantially in the form of a disk having a circular opening formed centrally therein. A ring 17 is however secured to the web portion by means of ears 18 which are formed integral with the web portion and to which the ring is attached and the said ring is located beneath the web portion and in slightly spaced relation to the under faces of the blades so that the space is formed between the ring and the channels in the blades to permit passage of the air.

It is to be understood that I do not desire to be limited to the exact details of construction shown and described, for obvious modifications will occur to a person skilled in the art.

What is claimed is:—

- 25 1. A toy of the class described comprising an apertured web portion and longitudinally channelled blades radiating from the web portion.
2. A toy of the class described comprising a web portion and channelled blades radiating from the web portion.

3. A toy of the class described comprising a channelled and apertured web portion and channelled blades radiating from the web portion.

4. A toy of the class described comprising an apertured web portion and channelled blades radiating from the web portion, the channels in the blades being in communication with the aperture in the web portion.

5. A toy of the class described comprising an apertured web portion and longitudinally channelled blades radiating from the web portion, the web portion being located in a different plane to that in which the ends of the blades are located.

6. A toy of the class described comprising an apertured web portion and longitudinally channelled blades radiating from the web portion, the web portion being located in a higher plane than that in which the ends of the blades are located.

7. A toy of the class described comprising an apertured web portion and channelled blades radiating from the web portion in inclined planes.

8. A toy of the class described comprising an apertured web portion and channelled blades radiating from the web portion, said blades being formed of sheet material creased longitudinally.

9. A toy of the class described comprising an apertured web portion and channelled blades radiating from the web portion, the said blades being formed of sheet material creased longitudinally and in alignment with the center of the aperture in the blade.

In testimony whereof, I affix my signature, in presence of two witnesses.

GOVERNIER W. MORTON.
